UNITED STATES PATENT OFFICE.

ALFRED MANSFIELD, OF VICTORIA, BRITISH COLUMBIA, CANADA.

FUEL-SAVING DEVICE FOR DOMESTIC STOVES AND RANGES.

Application filed September 15, 1920. Serial No. 410,368.

To all whom it may concern:

Be it known that I, ALFRED MANSFIELD, of the city of Victoria, in the Province of British Columbia, Canada, having invented certain new and useful Improvements in Fuel-Saving Devices for Domestic Stoves and Ranges, do hereby declare that the following is a full, clear, and exact description of the same.

10 My invention relates to improvements in fuel saving devices for cooking stoves and ranges, in which a temporary modification of the fire-box or fire space is made in order to effect conservation of fuel. Fuel savers 15 of the type in question hitherto in use have taken the form of a removable fire-grate practically covering the entire bottom surface of the fire-box but raised above it so as to reduce the capacity of the fire space; this 20 device whilst reducing the fire space has the disadvantage that the fuel is dissipated over the entire length of the fire-box, and when the full capacity of the fire-box is required this device must first be removed, also other 25 obvious disadvantages which in my invention are entirely eliminated.

The primary purpose of my invention is to provide an improved fuel saving device 30 of the type adapted to be inserted in the fire box of an ordinary cooking stove or range when it is desired to effect a temporary reduction in the capacity of the fire box for the purpose of conserving fuel.

Another purpose of the invention is to so 35 construct the fuel saver, that the same will occupy only a predetermined area of the fire box when inserted therein, so that the capacity of the fire box may be increased without removing the fuel saver simply by introducing 40 additional fuel into the unoccupied portion of the fire box.

Other objects and advantages of the invention, as well as the particular construction, combination and arrangement of parts 45 will be more readily understood from the following description and accompanying drawings;

In the drawing, the single figure is a front 50 perspective view of the improved fuel saver positioned within the fire box of an ordinary cooking stove or range, the latter being shown in dotted outline.

Referring more particularly to the drawings, 55 5 and 6 designate respectively a pair of upright end plates of unequal height resting at their lower edges on the bottom of the

fire box A and spaced apart a distance approximating one-half the length of the fire box. These plates support between them a horizontally disposed perforated grate or 60 plate 7, which is preferably supported above the bottom of the fire box a distance approximating substantially one-half the height of the latter so that, in the use of this device, the fuel capacity provided will be equal to 65 approximately one-fourth of the normal fuel capacity of the fire box, it being understood that the fuel is supported on the plate 7 and retained thereon by the upwardly projecting portion of plate 5 in cooperation with the 70 sides and opposing end wall of the fire box.

The plates 5, 6 and 7 are constructed to extend the full width of the fire box A, but it will be noted that the plate 5 is made substantially higher than the plate 6, so as to 75 extend from the top to the bottom of the fire box and thus constitute a baffle positioned substantially intermediate the length of the fire box. In constructing the device, it will be understood that the plates 5, 6 and 7 may 80 be cast in one piece or formed separately and assembled in any desired manner. In the present instance, it will be noted that one end of the plate 7 is flanged and secured to the plate 5 intermediate the upper and lower 85 edges of the latter, the remaining end of the plate 7 being secured to the upper edge of the shorter end plate 6 and this latter end plate may, if desired, be perforated in any suitable manner for purpose of lightness 90 and conservation of material.

In practice, it will be understood that the device is inserted in the fire box as disclosed in Fig. 1 with the end plate 6 lying against one end of the fire box and the remaining 95 end plate 5 lying substantially at a point intermediate the length of the fire box. The fuel is then placed on the plate 7 and is supported by the latter sufficiently close to the top of the fire box to afford maximum heat- 100 ing effect. In the event that a material increase in the capacity of the fire box is required, while the fuel saving device is positioned therein, this can be readily effected by introducing fuel into that portion of the fire 105 box which is unoccupied by the fuel saving device and without necessitating removal of the latter.

By forming the plate 5 to provide a baffle extending the full width and height of the 110 fire box A, a strong draft will be created through that portion of the bottom of that

fire box directly underlying the perforated plate 7 to effect complete combustion of the fuel.

What I claim, and desire to secure by Letters Patent, is—

A fuel saver for insertion in a fire box, comprising a pair of end plates adapted to rest at their lower edges on the bottom of the fire box at one end of the latter, said plates being of unequal height and spaced

apart a distance approximating one-half the length of the fire box, a perforated body plate secured at one end upon the upper edge of the shorter of the end plates and at the opposite ends to the intermediate portion of the remaining end plate, the last mentioned end plate, being of sufficient height to extend from the bottom to the top of the fire box.

ALFRED MANSFIELD.
